M. J. TRUMBLE

APPARATUS FOR REFINING OIL

Filed Sept. 2, 1924

Fig. 1.

INVENTOR:

MILON. J. TRUMBLE.

BY.

Fred A. Kamm
ATTORNEY.

UNITED STATES PATENT OFFICE.

MILON J. TRUMBLE, OF LOS ANGELES, CALIFORNIA.

APPARATUS FOR REFINING OIL.

Application filed September 2, 1924. Serial No. 735,356.

My invention relates to the art of refining hydrocarbon oils, and more particularly to the refining and cracking of heavy hydrocarbons. It is a well known fact that in handling many types of heavy oil, the residuum from the refining or cracking operation is either solid or semi-solid, sticking and caking in the still, which soon has to be shut down and cleaned due to the deposits therein.

An object of my invention is to provide means by which very heavy oils may be refined and cracked without trouble from deposits, these deposits being mechanically removed as fast as formed.

A still further object of my invention is to provide a still which will be electrically heated so that the temperature can be exactly regulated at all times.

Further objects and advantages will be made evident hereinafter.

Referring to the drawing which is for illustrative purposes only,

Fig. 1 is a sectional side elevation of the apparatus.

Fig. 2 is a transverse section of the same.

In the drawing 11 is a closed chamber having tight ends 12 and 13. Bearings 14 and 15 are secured to the ends 12 and 13, being electrically separated therefrom by insulation 16. Each of the bearings 14 and 15 are provided with a stuffing box 17 fitting about a stub shaft 18. On the inner end of each of the stub shafts 18 is a metal disc 19, these discs being connected by means of a metal cylinder 20. A current of electricity is delivered to the shafts 18 by collector rings 30, having brushes 31 supplied with current from a secondary 32 of a trans-

former 33. Located directly above the cylinder 20 is a perforated pipe 40 supplied with the heavy hydrocarbon through a valve 41. The cylinder 20 is rotated in the direction of the arrow B of Fig. 2 and a scraper 42 insulated from the outer casing is provided in the position shown in that figure. Situated below the cylinder 20 under a protecting hood 50 is a vapor outlet pipe 51 which has perforations 52 in the top thereof, this pipe extending through the end 13 and being provided with a valve 53. The cylinder 20 is turned slowly by means of an insulated gear wheel 55 from any convenient source of power.

The method of operation of the invention is as follows:

The cylinder 20, being turned slowly, the heavy hydrocarbon is delivered on the top thereof through the pipe 40, the rate of flow being controlled by a valve 41. In case asphalt or other heavy bituminous matter is to be treated, it may be heated for the purpose of reducing its viscosity before being delivered to the pipe 40. This heavy material is delivered on the top of the cylinder 20 in a thin film which is somewhat adherent so that it flows and is carried around as shown in Fig. 2.

The current from the secondary 32 of the transformer 33 passes from the brushes 31 to the collector rings 30 through the stub shafts 18 to the discs 19, the cylinder 20 completing the circuit. This cylinder may be made of any metal but I have found that mild steel pipe is quite satisfactory for the purpose. A potential of from ten to thirty volts and a current of approximately ten thousand amperes is sufficient to heat a 10 inch cylinder 10 feet long. This resistance heating can be exactly regulated by regulating the current supplied which may be controlled by any convenient means, not shown. The hydrocarbon adhering to the highly heated surface is subjected to a combined distilling and cracking action, the vapors being readily driven off from the thin film into the interior of the chamber 11, these vapors being withdrawn through the pipe 51. A portion of the hydrocarbon in many cases will adhere to the cylinder in the form of a very heavy tar or even coke. This material is constantly scraped off by the scraper 42, falling into the bottom of the member 11, from which it may be readily removed through convenient handholes.

It will be noted that by my process I am able to heat very heavy hydrocarbons in a thin film and that I am able to provide a continuous process in which the heavy carbon residues are removed mechanically from the heating surface soon after being formed.

It will further be noted that I provide a thin film on an electrically heated surface, the temperature of which can be accurately controlled at all times.

It will be further noted that by a suitable manipulation of the valve 53, I am able to maintain and regulate the pressure inside the apparatus so that the whole operation can be carried under pressure if desired.

I claim as my invention:

1. In an evaporator for treating petroleum

oils, the combination of: a cylinder; two shafts, one projecting from one end of said cylinder and the other projecting from the other end of said cylinder, said shafts having a common axis about which said cylinder rotates; a tight casing enclosing said cylinder; an oil inlet means for delivering oil onto said cylinder; a vapor outlet means for withdrawing oil vapor from said casing; two bearings, one supporting one of said shafts and the other supporting the other of said shafts; means for electrically insulating said bearings from said casing and means for impressing an electromotive force between one end of said cylinder and the other end of said cylinder.

2. A device as in claim 1 in which the

means for impressing an electromotive force between one end of said cylinder and the other end of said cylinder includes: two collector rings, one mounted on one of said shafts and the other mounted on the other of said shafts; two brushes, one bearing on one of said collector rings and the other bearing on the other of said collector rings; and means for impressing an electromotive force between said brushes.

3. A device as in claim 1 in which said shafts are surrounded by collector rings which are entirely outside said casing.

In testimony whereof, I have hereunto set my hand at Los Angeles, California, this 26th day of August, 1924.

MILON J. TRUMBLE.
